UNITED STATES PATENT OFFICE.

CURT BUCHMÜLLER, OF BERLIN, GERMANY, ASSIGNOR TO A E G-DEUTSCHE WERKE,
AKTIEN-GESELLSCHAFT, OF BERLIN, GERMANY.

TYPEWRITER.

Application filed July 3, 1924, Serial No. 724,039, and in Germany April 23, 1923.

My invention relates to typewriters and more especially to mechanism for lifting the carriage of typewriters in which the carriage is locked after having been lifted.

Mechanism of this type, as heretofore devised, comprises a key for lifting the carriage, a second key for releasing the carriage and allowing it to be lowered so as to return to its normal position, and a third key for spacing. As a rule this third key is represented by a long spacing bar arranged in front of the key board.

In my improved mechanism a separate spacing key is dispensed with and the operation of spacing is performed by the lifting and the releasing key, respectively.

When the carriage is in its normal position it is spaced by depressing the releasing key. In the lifted position the carriage is spaced by depressing the lifting key. This key is free to return to its initial position after lifting the carriage without interference by the locking means. Consequently the lifting key can be operated as often as desired for spacing while the carriage remains locked in its lifted position.

This is effected by operating the carriage lifting mechanism through the medium of an arm which is free to return to its initial position with the lifting key leaving the carriage in lifted position.

The lifting and releasing keys are connected with the spacing mechanism by means adapted to transmit motion from the keys to the spacing mechanism, but not vice versa. I prefer employing to this end spring-actuated clutches the springs of which are weaker than the pull back springs which hold the lifting and releasing keys in their normal positions.

My improved mechanism offers the advantage that a separate spacing key requiring being operated every time the carriage is lifted and returned to its normal position is dispensed with altogether. Moreover, a typewriter according to my invention can be substituted without any

change for the well known recording telegraph having a key board similar to that of the perforator. The recording telegraph writes small letters in one position and figures and points in the other. The key board is connected with the types by electric means and the messages are printed on a strip which must be cut and pasted on a telegram form.

A typewriter comprising the novel lifting mechanism can be used without difficulty by operators trained to the key board of the perforator and messages received by means of a head receiver, for instance, can be written on a telegram form exactly as in a normal typewriter.

In the drawings affixed to this specification and forming part thereof a mechanism embodying my invention is illustrated diagrammatically by way of example.

In the drawings Fig. 1 is an isometric view of my improved mechanism;

Figs. 2 and 3 are an axial section and a transverse section on the line A—B in Fig. 2, respectively, of a resilient clutch connecting the shafts of the lifting and releasing keys with the spacing mechanism;

Figs. 4, 5, 7, and 8 are details of parts of the clutch shown in Figs. 2 and 3;

Fig. 6 is an isometric view of the spacing lever, and

Fig. 9 is a similar view of a typewriter provided with my improved mechanism.

Referring to the drawings, on a hollow shaft *b*, which is rotatably carried on a solid shaft *c* in a frame *I* of the typewriter, there are fixed the lifting key *a*, a lifting arm *d* connected with a pull back spring *e* and one half *f* of a resilient clutch *f*, *m*.

The releasing key *g* a releasing arm *h* for rendering inoperative the locking pawl *i* of the lifting lever *p* and one half *k* of a second resilient clutch *k*, *n* are fixed on the solid shaft *c*. The boss *L* of a spacing lever *l* (Fig. 2) on which are fixed the clutch halves *m* and *n* with their springs *r* and *s* is loosely

mounted on the shaft *c* between the halves *f* and *k*.

The lifting lever *p* is fulcrumed at *o* with frame I of the typewriter and provided with pins *q* and *q'* for engagement with the lifting arm *d* and the pawl *i*, respectively, and a pull back spring *p'*. A link *p''* connects the lever *p* with the carriage II of the typewriter. The means for transmitting the motion of the key *a* to the carriage II are well known in the art and are therefore not described and shown in detail.

The pawl *i* has the form of a three-armed lever fulcrumed at *i'* in the frame I of the typewriter and provided with a pull back spring *t*. One arm of the pawl *i* is formed with a hook adapted to engage the pin *q'* of the lever *p*; the other arm carries a pin *i''* adapted to be engaged by the hook-shaped end of the releasing arm *h*.

The operation of this mechanism is as follows:—

When the lifting key *a* is depressed, the lifting arm *d* on the hollow shaft *b* engages the pin *q* on the lifting lever *p*, turning the lever on its fulcrum *o* and lifting the carriage II by means of the link *p''*. When the carriage II is in its lifted position, the hook of pawl *i* engages the pin *q'* of lever *p* and locks the latter so that the carriage is maintained in its lifted position. At the same time the spacing lever *l* is actuated through the medium of the clutch half *f* fixed on the shaft *b*, the spring *r* and the second half *m* fixed on the boss *L* of the lever *l*. It will be understood that the carriage is fed one space on being lifted. The movement of the lever *l* is transmitted to the spacing mechanism by any suitable means, for instance by an angle lever *l'* and a link *l''*, these means being also well known in the art and therefore not described and shown in detail.

While the carriage is in its lifted position, types can be written and the carriage can be spaced as often as desired by depressing the lifting key *a*. When the key *a* is so depressed, only the spacing lever *l* will be operated by the clutch half *f* and will space the carriage, while the lifting arm *d* on the hollow shaft *b* does not act on the locked lifting lever *p*. After each operation the spring *e* returns the key *a* to its initial position.

If it is desired to return the carriage II to its normal position, the releasing key *g* is operated. This causes a downward movement of the arm *h* which is mounted on the same shaft *c* with the key *g*, and rotation of the pawl *i* on its pivot *i'* so that its hook releases the pin *q'* of lever *p*, and the carriage returns to its normal position under the action of gravity. At the same time the spacing lever *l* is actuated by means of the clutch half *k* and the spring *s* and the

carriage is fed one space. The movement of the coupling half *k* is transmitted to the lower half *n* by the spring *s*. As the halves *n* and *m* are rigidly secured on the boss of the spacing lever, the latter is actuated. Types can now be written or the carriage can be spaced by depressing the key *g* as often as desired.

The pull back spring *t* of pawl *i* returns the key *g* to its normal position after it has been operated. The springs *r* and *s* of the couplings *f*, *m* and *k*, *n* are weaker than the pull back springs *e* and *t* in order to prevent operation of both keys when one of them is depressed.

I wish it to be understood that I do not desire to be limited to the exact details of construction shown and described, for obvious modifications will occur to a person skilled in the art.

I claim:—

1. Typewriter comprising a carriage, means for lifting said carriage, means for locking said lifting means, means for releasing said lifting means, means for spacing said carriage, a key for operating said lifting means, another key for operating said releasing means, a spring connected with each key for returning it to inoperative position and means inserted between said keys and said spacing means for transmitting motion from said keys to said spacing means, said transmitting means being weaker than said springs.

2. Typewriter comprising a carriage, means for lifting said carriage, means for locking said lifting means, means for releasing said lifting means, means for spacing said carriage, a key for operating said lifting means, another key for operating said releasing means, a spring connected with each key for returning it to inoperative position and a spring-actuated clutch inserted between said keys and said spacing means for transmitting motion from said keys to said spacing means, said clutch being weaker than said springs.

3. Typewriter comprising a carriage, means for lifting said carriage, means for locking said lifting means, means for releasing said lifting means, means for spacing said carriage, a key for operating said lifting means, another key for operating said releasing means, a shaft carrying said lifting key, another shaft carrying said releasing key and said releasing means and means inserted between said keys and said spacing means for transmitting motion from said keys to said spacing means, while being inoperative in the reverse direction.

4. Typewriter comprising a carriage, means for lifting said carriage, means for locking said lifting means, a lifting arm adapted to act on said lifting means, a releasing arm adapted for rendering inoper-

ative said locking means, a spacing lever, a shaft having keyed to it said lifting key and said lifting arm, another shaft having keyed to it said releasing key and said releasing arm, said lifting key and the boss of said spacing lever being loose on said other shaft, one half of a spring clutch being fixed on one, one half of another spring clutch being fixed on the other shaft, the other halves of said clutches being fixed on 10 said boss and springs for returning said keys to inoperative position, said springs being stronger than said clutches.

In testimony whereof I affix my signature.

CURT BUCHMÜLLER.
